UNITED STATES PATENT OFFICE.

WILLIAM J. ZIETLOW, OF CEDARBURG, WISCONSIN.

CURTAIN POLE AND HANGER.

1,074,683.

Specification of Letters Patent.

Patented Oct. 7, 1913.

Application filed April 21, 1913. Serial No. 762,682.

To all whom it may concern:

Be it known that I, WILLIAM J. ZIETLOW, a citizen of the United States, residing at Cedarburg, in the county of Ozaukee and 5 State of Wisconsin, have invented certain new and useful improvements in Curtain Poles and Hangers, of which the following is a specification, reference being had to the accompanying drawings.

10 This invention relates to new and useful improvements in combined curtain hangers and supports, the object of the invention being to provide a novel curtain hanger for supporting various kinds of curtains and 15 also to provide a novel one piece support for supporting the ends of the hanger.

Another object of the invention is to provide a combined hanger and support of the above character which will possess advantages in points of efficiency and durability, is inexpensive of manufacture and at the same time is simple in construction and operation.

20 With the above and other objects in view, the invention consists in the novel features of construction and the combination and arrangement of parts to be hereinafter more fully described, pointed out in the claims and shown in the accompanying drawings, 25 in which—

Figure 1 is a side elevation of a curtain pole and hanger constructed in accordance with my invention and illustrating the manner of use; Fig. 2 is a vertical sectional view 30 of the hanger; Fig. 3 is a top plan view of the hanger; Fig. 4 is a front elevation; Fig. 5 is a cross section taken through the pole; and Fig. 6 is a side elevation illustrating a modified form of hanger.

35 Referring more particularly to the drawings, 1 indicates the door frame and secured upon each side of the frame and arranged upon the inner face thereof are my improved hangers, each hanger comprising a single piece of material which comprises the body portion 2 having an opening at one end thereof, as shown at 3, whereby the same may be secured by means of a screw or other suitable means and the inner face of 40 the door frame. Formed integral with the body 2 and projecting outwardly at right angles therefrom are the side portions 4, which are arranged in spaced parallel relation and between which the ends 45 of the curtain pole 5 are arranged. Formed integral with the side portions 4 at the outer

ends thereof are the supporting arms 6, which project inwardly from the side portions and upon which the ends of the pole 5 are mounted.

Formed integral with the body 2 at the lower end thereof is a resilient tongue 7, which projects upwardly from the bottom of the body and is arranged in spaced parallel relation therewith, said tongue frictionally 50 engaging the end of the pole 5 to securely hold the same upon the supporting arms 6. From the above it will be readily apparent that when the ends of the pole 5 are arranged between the side portions 4 and 55 mounted upon the arms 6, the spring tongues 7 will frictionally engage the ends of the pole and prevent the removal of the same until force is applied thereto.

Another object of the invention is to provide a combined hanger and support of the above character which will possess advantages in points of efficiency and durability, is inexpensive of manufacture and at the same time is simple in construction and operation.

25 My improved curtain hanger comprises 75 the pole 5, upon which is mounted the upper ends of the curtains 8, the upper ends of the curtains being passed around the pole and the same secured to the body of the curtain, forming a pocket 9 in which the pole 5 is arranged. The upper ends of the curtains are securely held against displacement by means of a resilient metal guard 9, which is engaged over the upper side of the pole and is adapted to be of 80 sufficient resiliency to clamp the curtains to the pole, thus holding them against movement upon the same.

In Fig. 6, I have illustrated a slightly modified form of support, which is constructed of a single strip of metal, one end of which is secured to the outer edge of the door frame 1, by means of a screw 10 or other suitable fastening means may be employed, if desired. The strip comprising 90 my improved form of support is then bent outwardly in a horizontal plane, as shown at 11, thence curved to form a pole receiving socket 12. The end of the strip is then bent downwardly and upwardly, the extreme end being arranged above the mouth 13 of the socket and curved outwardly, as shown at 14, to form a finger engaging member. The ends of the curtain pole 5 may be readily inserted within the socket 100 12 by pressing downwardly upon the finger engaging member 14 which will open the mouth portion 13 and allow the end of the curtain pole to be inserted into the socket, the resiliency of the metal strip closing the 105 mouth 13 after the finger engaging member 14 has been released.

From the above description taken in connection with the accompanying drawings, it will be readily apparent that I have provided a simple and durable curtain hanger support whereby curtains of various kinds may be quickly suspended in a door way or other similar place or readily removed therefrom.

It will also be apparent that when the curtain hanger is arranged in position, the same is securely held against accidental displacement, but the same may be readily removed when force is applied thereto.

It will also be apparent that my device is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claims.

What I claim is:—

1. A support comprising a body portion, spaced parallel side portions formed in-

tegral therewith, inwardly projecting supporting arms formed at the outer ends of the side portions, a resilient tongue formed integral with the body and arranged between the side portions, said tongue being adapted to engage the end of a curtain pole when arranged between the side portions to securely hold the same in place.

2. A support including a body provided at one end with an opening, spaced parallel side portions formed at the other end of said body and projecting at right angles thereto, supporting arms formed at the outer ends of said side portions, a resilient tongue formed integral with the lower end of the body and bent upwardly and arranged in spaced parallel relation therewith, said tongue frictionally engaging the end of a curtain pole to securely hold the same in position between the side portions.

In testimony whereof I hereunto affix my signature in the presence of two witnesses.

WILLIAM J. ZIETLOW.
